TYPEWRITER TYPE BAR ACTION

Laurence B. Hill and George R. Kunzelman,
Syracuse, N. Y., assignors to Smith-Corona Inc.,
Syracuse, N. Y., a corporation of New York

Application January 19, 1952, Serial No. 267,234

20 Claims. (Cl. 197—30)

1

The invention relates to improvements in typewriter type bar actions and, more particularly, to key driven and spring returned actions for actuating individually the type bars of a system of pivoted front strike type bars in which the bars normally are cumbent and arrayed in an arc which curves upward from the middle to the sides of the system.

The keys of the system of individual operating actions for such a system of type bars are commonly arranged in stepped and straight banks or rows, usually four banks, which extend transversely of the typewriter at the front thereof. Such type bar and key systems present extremely difficult problems with respect to attainment of such desirable ends as smooth and like rapid acceleration of the printing strokes of all of the type bars with sharp printing impact and quick type bar return, uniform operating dip or depression of all keys, uniform and light or easy starting touch for all keys, a like progressively increasing key resistance to finger depression by all keys, and a like final cushioning absorption of the momentum of a typist's finger by each actuated key at the end of the printing stroke of its associated type bar.

The invention provides an improved system of type bar actions and improved individual type bar actions for the attainment of the foregoing primary ends and other ends hereinafter pointed out.

The improved type bar action system also is characterized by provision for uniform operation of all of the type bar actions on a straight universal bar, by an improved arrangement of two sets of type bar action returning springs, by improved means whereby the typist may vary the key touch at will, by its compact and inexpensive construction, and by its adaptability for use in a typewriter in which the type bars are pivoted in a case shiftable segment and in a typewriter in which the segment is disposed in a rearwardly inclined plane for increased visibility of the writing line and to reduce the overall height of the machine.

In the accompanying drawings:

Fig. 1 is a fragmentary vertical sectional view of an otherwise known typewriter equipped with a system of type bar actions embodying the invention in its preferred form, the view being taken medially of the system of actions on the line 1—1 of Fig. 2;

Fig. 2 is a fragmentary top plan view of the typewriter with certain parts omitted, and others broken away, for clarity of illustration of features of the invention;

2

Figs. 3 and 4 are diagrammatic views illustrating the operation respectively of one of the type bar actions at the middle of the system and one of the actions adjacent a side of the system, both of which actions have second bank operating keys;

Fig. 5 is a diagrammatic view on an enlarged scale four times that of Figs. 1 to 4 and illustrating the system of returning springs for the key levers supporting the four different banks of keys;

Fig. 6 is a diagrammatic view on the same scale as Fig. 5 showing how the actions are varied in accordance with the key bank in which their keys are located;

Fig. 7 is a diagrammatic view on a scale three times that of Figs. 1 to 4 showing how the actions are varied in accordance with their locations between the middle and sides of the system; and

Fig. 8 is a detail sectional view on the line 8—8 of Fig. 1 showing features of the means variably settable by a typist to uniformly and simultaneously vary the touch of all of the keys.

The improvements are shown embodied in a known kind of typewriter having a type bar segment which is disposed in a rearwardly inclined plane, which normally is positioned for lower case typing, and which is case shiftable downwardly for upper case typing. It will be obvious to those skilled in the art that the invention may be embodied in a platen shift typewriter and in a typewriter having a type bar segment which is disposed in a vertical plane. So much of the known typewriter shown, as is necessary to a clear understanding of the invention now will be described.

The typewriter has a platen roller 10 supported by a platen carriage (not shown) to travel endwise transversely of the typewriter above the rear portion of a stationary main frame of the typewriter. The main frame comprises vertically disposed left and right hand side plates 11 and 12 and a rearwardly inclined cross plate 13 connected to said side plates with the upper edge of the cross plate underlying the platen roller.

A type bar segment 14, having the usual arcuate fulcrum rod 15 about which the type bars 16 swing, and also having the usual radial guiding and spacing slots 17 for the type bars, is fixedly held in known manner to a rearwardly inclined and case-shiftable carrier plate or segment support 18 located at the front face of the cross plate. The carrier plate, the segment and the type bar fulcrum rod all lie in rearwardly inclined planes parallel to that of the cross plate 13, said planes in the machine shown being in-

clined rearwardly at an angle of twelve and one-half degrees to the vertical.

The carrier plate is supported, by means not shown, for downward shifting from its normal position shown in Fig. 1 to a lower position in the same plane to condition the machine for upper case typing. The normal position of the carrier plate is determined by the engagement of a stop 19 with a stop lug 20 which projects rearward from cross plate 13. Stop 19 is carried by a lug 21 which projects rearward from the carrier plate through a clearance aperture 22 in the cross plate. Downward shifting of the carrier plate is arrested by the engagement of a stop 23 with the stop lug 21 on the carrier plate, the stop 23 being offset laterally relatively to stop 19 and carried by a lug 24 which projects rearwardly from the cross plate.

The type bars 16 normally are supported in cumbent slightly upwardly and forwardly inclined positions in an arcuate array which is determined, as usual, by the arcuate fulcrum rod, by the radially slotted segment and by an arcuate rest 25 for the type carrying arms of the type bars. Said rest, as is usual in typewriters of the kind shown, is held to the segment carrier plate by a pair of side arms to shift with the carrier plate, one of said side arms being shown at 26 in Fig. 1. In the typewriter shown, the rest 25 supports each of the type bars for a throw of 93 degrees from rest to printing position. The main type carrying arms of the type bars each carry a lower case type and an upper case type, and each type bar is extended rearward, as usual, beyond its fulcrum to form a type bar heel or short operating arm 16a for connection with an associated key-operated action which exerts a forward pull on the operating arm 16a to swing the type bar to printing position. The operating arms 16a are all of identical length and each makes the same angle with the type carrying arm of the type bar of which it is a part. The segment supports the bars, as is usual in the kind of typewriter shown, to print at a common printing point on a horizontal printing line which extends longitudinally of the platen roller somewhat above the level of the axial line of the platen roller. The two middle type bars of the system are located equidistant from the lowest point in the arc of the fulcrum rod 15 and from the medial vertical longitudinal plane of the machine containing the section line 1-1 in Fig. 2.

Certain features of the improved system of type bar actions which are known in the art first will be described.

The heel of each type bar is connected by a pivot 27 with the rear end of a different one of a system of pull links 28, and the forward end of each link 28 is connected by a pivot 29 to the upper end of a different one of a system of sub-levers 30 of the third class. The sub-levers 30 are fulcrumed at their lower ends on a common straight and horizontal fulcrum rod 31. Fulcrum rod 31 is held in a rear portion of a sub-lever fulcrum bar 32 which extends across the lower portion of the main frame below the system of type bars and is held to the main frame side plates 11 and 12 by screws 33, said rear portion of the bar being provided with vertical spacing slots 34 for the sub-levers 30. The two middle ones of the sub-levers 30 of the system are located equidistant from the medial vertical longitudinal plane of the machine containing the section line 1-1 in Fig. 2, these two sub-levers being of equal length and

having their link pivot connections 29 equidistant from fulcrum rod 31.

The sub-levers 30 are graded progressively upward in length from the two middle sub-levers to the two side sub-levers of the system and the upper portions of the sub-levers are bent laterally to conform with the arc of the type bar heels, so that all of the pivots 29 lie in an arc which is concentric with the arc of the type bar fulcrum rod and with the arc in which the pivots 27 lie. These arcs lie in parallel planes with the two pivots 27, 29 of each link in substantially the same vertical plane fore and aft of the machine. The rear pivot 27 of each link is arranged to shift to points equal distances below and above a line normal to said parallel planes in case shifting the segment respectively from and back to normal position. The links 28 swing about their front pivots 29 during case changing, and the distance between pivots 27 and 29 is identical for all of these links.

First, second, third and fourth bank key levers 35a, 35b, 35c and 35d, respectively, of the system of key levers support the first, second, third and fourth bank type keys 36a, 36b, 36c and 36d, respectively, of the usual standard four bank keyboard. The key levers decrease in length from the first bank to the fourth bank, as usual, and all are fulcrumed at their rear ends on a common fulcrum rod 37 which is straight and extends horizontally across the machine. Rod 37 is carried by the upper portion of a key lever fulcrum bar 38 which extends across the machine, which is held to the main frame side plates by screws 39, and which is provided with vertical spacing slots 40 for the rear ends of the key levers. Adjacent the rear of the keyboard the key levers are spaced by a key lever guide comb 41 which extends horizontally across the machine, which is held to the main frame side plates by screws 42, and which supports a straight horizontal cushioning stop 43, which stop extends transversely across the machine and normally is abutted by the upper edges of the key levers to determine their returned or rest positions.

The improved features of the individual type bar actions and of the system of said actions now will be described with reference to the preferred embodiment of the invention illustrated in the drawings.

To provide a more compact type bar action system located wholly forward of the intermediate across plate 13 of the main frame, the key lever fulcrum bar 38 preferably is located closely in front of the lower part of said cross plate and extends across the lower portion of the main frame below the system of type bar action links 28 and behind the sub-lever fulcrum bar 32. While the key lever fulcrum bar may be located adjacent the rear end of the main frame to there extend across the lower portion of the frame, as is more common in the art, the location shown is preferred notwithstanding the fact that it results in substantial shortening of the key levers, one advantage of the improved system being that it makes possible the successful use of short key levers while retaining a short uniform key dip and avoiding undue tilting of the keys on their printing strokes, as more fully hereinafter explained.

The sub-lever fulcrum bar 32 has a forward portion which carries a straight fulcrum rod 44 that extends horizontally across the machine forward of and parallel to the fulcrum rod 31 and passes under the forward portions of the several type bars. Rod 44 is a common fulcrum for a

second system of sub-levers which are levers of the first class and are engaged in spacing slots 45 formed in said forward portion of the sub-lever fulcrum bar. Each of these sub-levers is a bellcrank and, in the normal rest positions of the type bar actions, one arm of each bellcrank extends rearward and upward from the bellcrank fulcrum rod and the other arm extends forward and downward from said fulcrum rod. These bellcranks are located behind the keyboard in a zone forward of the system of sub-levers 30 and are spaced along their fulcrum rod in accordance with the spacing of the sub-levers 30 along their fulcrum rod.

Each bellcrank has its normally rearwardly and upwardly extending arm 46 connected to a different one of the sub-levers 30 by a different one of a system of normally rearwardly and upwardly extending pull links 47. These links all are of identical lengths and each link has a pivotal connection 48 with a different one of said bellcrank arms 46 and a pivotal connection 49 with a different one of said sub-levers 30, these pivotal connections being arranged as more fully hereinafter explained. For reasons hereinafter explained, the arms 46 of all of the bellcranks preferably are of identical size and shape and normally are in axial register across the machine.

Each key lever of the system of key levers is a lever of the second class, each key lever being connected intermediate its key and fulcrum with the normally forwardly and downwardly extending arm of a different one of the system of bellcranks by a different one of a system of pull links 50. The pull links 50 all are of identical length, and each link has a pivotal connection 51 with a different one of the key levers and a pivotal connection 52 with a different one of said forwardly and downwardly extending bellcrank arms. Each link 50 normally extends forwardly and upwardly from its pivotal connection 51 to its pivotal connection 52.

Preferably, and as shown, to save metal and still permit an arrangement of the sets of pivotal connections 51 and 52 hereinafter described, all of those bellcranks which are linked to the first bank key levers 35a have arms 46a of identical length and of identical normal forward and downward inclination, all of those bellcranks which are linked to the second bank key levers 35b have arms 46b of identical length and of identical normal forward and downward inclination, all of those bellcranks which are linked to the third bank key levers 35c have arms 46c of identical length and of identical normal forward and downward inclination, and all of those bellcranks which are linked to the fourth bank key levers 35d have arms 46d of identical length and of identical normal forward and downward inclination, but the lengths of the arms 46a, 46b, 46c and 46d, and also their normal downward inclinations, are increased slightly in the order of recitation of said arms, arms 46a being the shortest and having the least normal downward inclination and arms 46d being the longest and having the greatest normal downward inclination. However, it will be obvious from the following description that all of the bellcranks of the type bar action system may have those arms thereof which are linked to the key levers by the system of links 50 also formed of identical size and shape and located in axial register across the system in the normal positions of the type

bar actions provided only that said size and shape be such as to permit of the hereinafter described arrangement of said arms and links and the link pivots.

In typewriters having a system of graduated sub-levers of the third class connected by a system of links to an arcuate system of type bars to impart printing strokes of identical amplitude to the type bars, the angles of throw of the sub-levers must decrease as the lengths of the sub-levers increase, and all of the pivots connecting said links to the sub-levers must swing through arcs of identical chordal length. Since said link pivots all normally lie in a plane parallel to that containing the arcuate fulcrum rod for the type bars, they must swing to positions in a second and parallel plane to complete the printing strokes of the type bars. In the machine shown, link pivots 29 throw from the plane P1 to the plane P2, as indicated in Fig. 7, these planes being parallel to that containing the type bar fulcrum rod and being inclined rearward at an angle of 12½ degrees to the vertical.

An important feature of the invention resides in the arrangement of the bellcranks 46-46a, the links 47 and the link pivots 48 and 49 in accordance with a principle by which there is provided a system of congruent toggles by which the sub-levers 30 and pivots 29 are so driven that all of the pivots 29 will travel from plane P1 to plane P2 in time intervals of identical duration and at identical accelerating rates of speed in response to identical angular throws of the bellcranks at any single speed rate, and by which all of said toggles are connected to sub-levers 30 between their fulcrum and pivots 29 at constant leverage ratio points affording an identical purchase of all toggles on said sub-levers. The aforesaid principle now will be described with particular reference to the typewriter shown in the drawings wherein the toggles exert a pulling action on the sub-levers to impart printing strokes to the type bars.

The link pivots 49 constitute the movable anchors of the toggles, and the link pivots 48 constitute the hinge pivots connecting the toggle arms, which arms in turn comprise the links 47 and the bellcrank arms 46, respectively. Arms 46 have a common fixedly located pivotal anchor which comprises the bellcrank fulcrum rod 44 and is parallel to, and forward of, the fulcrum rod 31 of the sub-levers 30. The axes of the pivots 49 all lie on a cylindrical locus which is the periphery of an imaginary cylinder C1 whose axis is coincident with that of the bellcrank fulcrum rod 44. The pivots 49 normally lie on said locus at points between the sub-levers and bellcranks where the respective constant leverage arcs for the graduated sub-levers 30 intersect said locus, said arcs being struck about the sub-lever fulcrum rod 31 and some of them being indicated by the reference letter A in Fig. 7. In the machine shown, a constant leverage ratio of a fraction under 3 to 1 is selected as desirable, but of course a different ratio could be provided.

The link pivots 48, or hinge pivots of the toggles, are all located on a second cylindrical locus which is the periphery of a second imaginary cylinder C2 whose axis also is coincident with that of the bellcrank fulcrum rod 44. To provide pull toggles, the radius of the cylinder C2 is smaller than that of cylinder C1. Pivots 48 are located on the locus or cylinder periphery C2 at the points where straight lines of equal length will connect the axes of each pair of pivots 48-49.

By this arrangement, the effective lengths of all links 50 are identical and the effective lengths of all arms 46 are identical. Also the toggles will fold from congruent normal or starting conditions to congruent actuated or final folded conditions in actuating the sub-levers 30 to impart printing strokes to the type bars.

While an effective link length may be selected which is equal to the radial distance between the peripheries of the two cylinders C1 and C2, and thereby afford congruent toggles which normally are fully straightened and consequently normally would serve as anti-rebound toggle locks for the type bars, it is preferred to select a greater effective link length, as shown, so that said congruent toggles will have congruent slightly folded normal conditions in which the hinge pivots are displaced identical distances forward and upward from straight lines connecting the movable and fixed anchorages of the respective toggles. The preferred normal condition of the toggles improves the key touch. Pushing toggles could be provided according to the same principle by, for example, using a greater radius for cylinder C2 than for cylinder C1, or by locating the axis 44 of these cylinders behind axis 31, as will be obvious from the above explanation of the embodiment of the principle in the typewriter illustrated in the drawings.

A further important feature of the invention resides in the arrangement of the key levers, the bellcrank arms 46a, 46b, 46c and 46d, the links 50, and the link pivots 51 and 52 in accordance with a principle now to be described. These parts are so arranged that the links 50 and pivots 51 and 52, and the portions of the key levers extending from link pivots 51 to the key lever fulcrum rod 37 afford four sets or groups of toggles, one for each bank of keys, to actuate the bellcrank arms 46a, 46b, 46c and 46d to impart printing strokes to the type bars. On the down strokes of their acting keys these toggles act with rearward and downward pulling actions on the bellcrank arms to which they are connected. Each toggle includes a link 50 and that portion of a key lever which extends from the key lever fulcrum to the link pivot 51, the link 50 forming one arm of the toggle, said key lever portion forming the other arm of the toggle, the pivot 51 forming the hinge pivot of the toggle, the pivot 52 forming the movable anchor of the toggle, and the key lever fulcrum rod 37 forming a fixedly located pivotal anchor for all of the toggles and lying parallel to the bellcrank fulcrum rod 44.

The parts forming the said four sets of actuating toggles for the bellcranks are arranged so that the links 50 form toggle arms of identical effective length, that said key lever portions form toggle arms of identical effective length, and that all those toggles connected to keys in the same key bank are congruent toggles which have congruent slightly folded normal or starting conditions and which fold farther to congruent actuated or final conditions on the down strokes of the keys. The arrangement further is such that, although the lengths of the key levers vary in accordance with the banks in which are located the keys they carry, depression key strokes of like extent, like force and like speed will rock the bellcranks through like angles at like speeds and like rates of acceleration to effect complete printing strokes of the type bars, and that all of the keys will offer the same gradually increasing resistance to depression.

To the attainment of the ends just above set forth, all of the pivots 51 are connected to the key levers of the four banks 35a, 35b, 35c and 35d so as to be equidistant from the key lever fulcrum rod 37 and normally to be in axial alignment across the machine. All of the pivots 52 have their axes normally located on a locus which is the periphery of an imaginary cylinder C3 (Fig. 6) whose axis is the axial line in which the pivots 51 normally are located. This locus intersects four constant leverage arcs A1 (Fig. 6) which are of different radii and are struck about the axis of the bellcrank fulcrum rod 44. There is thus one of said arcs for each bank of keys.

The links 50 connected to the first bank key levers 35a have their pivots 52 connected to the bellcrank arms 46a to swing in that one of the arcs A1 having the shortest radius, the links 50 connected to the second bank key levers 35b have their pivots 52 connected to the bellcrank arms 46b to swing in the next succeeding one of the arcs A1, the links 50 connected to the third bank key levers 35c have their pivots 52 connected to bellcrank arms 46c to swing in the next succeeding one of the arcs A1, and the links 50 connected to the fourth bank key levers 35d have their pivots 52 connected to the bell crank arms 46d to swing in arc A1 having the longest radius.

All toggles of any group connected to key levers carrying keys in the same bank thus have congruent slightly folded or downwardly broken normal or starting conditions, the toggles in the group connected to the first bank or longest key levers being normally folded more than those in the other three groups, the extent of normal fold decreasing from group to group of toggles connected to the second, third and fourth bank key levers 35b, 35c and 35d in the order just recited. The toggle hinge pivots 51 are each carried downward and rearward upon depression of its connected key lever on a cylindrical locus which is the periphery of an imaginary cylinder C4 (Fig. 6) whose axis is coincident with that of key lever fulcrum rod 37, the extent of such movement being the same for all toggles connected to any one bank of key levers, and being least for first bank key levers and increasing from bank to bank for the second, third and fourth bank key levers. The additionally folded final or actuated conditions of all toggles of any group connected to key levers of the same bank are congruent but the extent of added folding varies with the key lever banks to which the group of toggles are connected, being least for the toggles connected to first bank key levers and increasing from key lever bank to key lever bank for toggles connected to the second, third and fourth bank key levers.

By the above-described arrangement the key purchase on the bellcranks through the medium of the bellcrank actuating toggles progressively decreases on the down strokes of the keys since the links 50 on said strokes move nearer into parallelism with the bellcrank arms to which they are pivoted. The key purchase on the bellcranks through the medium of said toggles also is the same for all keys regardless of the banks in which they are located, since the toggle purchase on the bellcranks varies for each bank of key levers in direct proportion to relative lengths of the key levers of different banks, such toggle purchase being least for the first bank, or longest, key levers and increasing for the second, third and fourth bank key levers.

From the foregoing description it will be ob-

served that, as indicated in Figs. 3 and 4, a full depression of any type key at a constant rate will actuate the sub-lever 30 connected to said key, and consequently the type bar connected to that sub-lever, at a speed which accelerates throughout said key depression. It also will be observed that the rear portion of the actuated key lever acts through the connected link 50 to impart an accelerated throw to the connected bellcrank, and that this acceleration is greatly augmented by the accelerating action of the arm 46 of the bellcrank and the link 47 which connects it to the sub-lever 30. This compound, or two-stage, acceleration assures a high speed type impact even for a relatively slow and easy depression of the key and thus enhances the clarity of the type impressions and permits the making of a maximum number of good carbon copies with a minimum key depression effort. It further contributes to successful use of short key levers with short key dip, since the extent of angular drive of any sub-lever 30 per equal increment of key dip is progressively and greatly augmented as its actuating key is depressed. As indicated in Figs. 3 and 4, depression of a key at a constant rate and in, for example, four equal steps, will cause the actuated bellcrank to rock through four progressively increasing steps and will cause the actuated sub-lever 30 to rock through four still greater and progressively increasing steps. The normal and final positions of the actions shown in Figs. 3 and 4 are indicated respectively in full lines and in dotted lines, and the termini of the first, second and third steps of movement of the key, bellcrank and sub-lever 30 are indicated by correspondingly numbered short lines.

Further features of the invention comprise the two systems of returning or retracting springs for the system of type bar actions, and the provisions for adjusting the normal tension of the springs of the two systems.

Different springs 53 of a system of helical tension springs of identical size, length and inherent power constitute the primary retraction springs for the type bar actions. The springs 53 all extend fore and aft of the machine parallel to the medial fore-and-aft vertical plane of the machine, have their rear ends hooked in anchor holes 54 in the rearwardly inclined upstanding flange portion 55a of a spring anchor bar 55, and have their forward ends hooked in anchor holes 56 in the respective sub-levers 30 below the laterally bent upper portions of the sub-levers. Flange portion 55a has an arcuate upper edge curved upwardly from its middle to its ends with the holes 54 adjacent said edge and equidistant therefrom. The anchor holes 54 all are located in one arc, and the anchor holes 56 all are located in a second arc. These arcs have the same radii, lie respectively in planes P3 and P4 (Fig. 7) parallel to plane P1, are concentric with the arc in which lie the pivots 29 at the upper ends of sub-levers 30, and have their lowest points in the medial fore-and-aft vertical plane of the typewriter. The two anchor holes 54, 56 for any one spring 53 occupy like positions in the arcs in which the respective holes are located, the holes 54 being spaced according to the spacing of the lower portions of the sub-levers 30.

By the aforesaid arrangement of the system of springs 53, all of said identical springs have the same tension in the retracted positions of the type bar actions, have their anchor holes 56 arranged to shift from plane P4 to a second and parallel plane P5 (Fig. 7) through arcs of like

chordal lengths to stretch the springs like extents on the printing strokes of the type bars, and have their anchor holes 56 arranged relatively to the sub-lever fulcrum rod 31 at constant leverage ratio points for application of like effective power to the sub-levers. On the printing stroke of any type bar, the stretching of the retracting spring 53 of the actuated type bar action is accelerated in direct proportion to the acceleration of the type bar so that the accelerated acquisition of kinetic energy by the type bar aids the stretching of the spring in such manner that a substantially constant resistance to key depression is offered by the spring which contributes to ease and lightness of the key touch.

While the spring anchor bar 55 may be fixed immovably to the main frame of the typewriter, it preferably is mounted for adjustment by the means shown into different selected positions to permit a typist to vary at will the normal key touch by varying simultaneously and uniformly the extent to which all of the springs 53 are stretched in the normal returned positions of the type bar actions.

To permit such adjustment of the normal stretch of springs 53, the anchor bar 55 is supported for adjustment in a path which is normal to the planes P1, P2, P3, P4 and P5 (Fig. 7) thereby to shift the spring anchors 54 while maintaining them in a plane parallel to the planes P4 and P5 in which the spring anchors 56 lie in the normal and actuated conditions respectively of the type bar actions. To so support and adjust the anchor bar the following described means are provided, said means being shown in Figs. 1, 2 and 8 and set for minimum key touch.

Extending fore and aft of the typewriter, and riveted, or otherwise fixed, to opposite ends of the anchor bar 55, are two end bars 57 having in their rear ends slots 58 which extend normal to the planes P1, P2, P3, P4 and P5 (Fig. 7) and also to the plane of flange portion 55a of the anchor bar. The key lever fulcrum rod 31 extends through slots 58 to support the end bars 57 at their rear ends to shift in the aforesaid path. To prevent lateral shifting of the slotted rear ends of the end bars, they are guided in slots 59 (Fig. 2) in the key lever fulcrum bar 32. To support the forward ends of the end bars to shift in said path, and to afford ready detachment of the anchor bar with its end bars, there is provided a rock shaft 60 which extends horizontally across the typewriter and has reduced ends 69a, and there are provided a pair of bearing brackets 61 which are fixed to the sub-lever fulcrum bar 32 and in which the reduced ends of said shaft are journalled, a pair of upstanding rock arms 62 and 63 fixed to said shaft, a pair of headed pivot studs 64 fixed to said rock arms equidistant from said shaft, and a pair of rearwardly extending slots 65 in the forward ends of the end bars 57 in which said studs 64 are engaged. Slots 58 and 65 are open at the adjacent ends of the end bars 57 to permit ready demounting of the anchor bar. The springs 53 urge the anchor bar forward to maintain the studs 64 at the rear ends of slots 65. The rock arms 62 and 63, and the headed studs 64, prevent lateral shifting of the forward ends of the end bars 57 of the anchor bar. The shaft is rockable to swing the rock arms 62 and 63 downward and rearward different distances from their limit position shown in the drawings and to carry the studs 64 rearward and downward in

a path substantially parallel to slots 58 and substantially normal to the planes P1, P2, P3 and P4.

To enable the typist to rock the shaft and rock arms, and to latch them in different selected positions to maintain the anchor bar in selectively adjusted positions, the left hand rock arm 62 is extended upward to a point adjacent the top of the typewriter and is formed at its upper end with a finger-piece or handle portion 62a. This finger-piece extends through a fore-and-aft slot 66 formed in a bracket 67, this bracket being fixed to the top portion of the left hand side plate 11 of the main frame. Arm 62 is a sheet metal arm having sufficient inherent resilience to maintain finger-piece 62a releasably latched in any desired one of a series of notches formed in the bracket 67 along the right hand edge of slot 66, the bracket shown having five notches with the setting indicating numerals 1, 2, 3, 4 and 5 provided on the bracket opposite the respective notches. Preferably, arm 62 is formed with a bent portion 62b which contacts the inner face of the main frame side plate 11 intermediate the bracket 67 and the stud 64 which is carried by said arm. This arrangement permits resilient flexing of the portion of the arm 62 above said bent portion 62b to unlatch the finger-piece 62a without straining or bending the end bar 57 with which said stud 64 on arm 62 is engaged. The end walls of slot 66 in bracket 67 are abuttable by the finger-piece to determine the limits of adjustment of anchor bar 55. In the position shown, the bar 55 is adjusted for light touch and anchors springs 53 so that they are slightly stretched while the several type bar actions are in normal returned condition.

The system of auxiliary type bar action returning or retracting springs 68 is provided to insure quick and full retraction of the key levers into contact with the key lever stop 43 and to insure normal maintenance of contact of the key levers with the stop. The auxiliary springs 68 are constructed, arranged and anchored as is now to be described for action of all of the springs with like effective force on the key levers and for simultaneous and uniform adjustment to vary their effective force. For over-all lightness of key touch, it is preferable to use springs 68 of a minimum force sufficient to slightly more than counterbalance the effect of gravity on the key levers.

Springs 68 are helical coil springs all of the same size, strength and length. Each spring is hooked at one end in an anchor hole 69 in the key lever it is to return, and is hooked at its other end in one of a series of anchor holes 70 in an adjustable spring anchor bar 71. Anchor holes 70 are arranged in a horizontal row across the typewriter adjacent the upper edge of anchor bar 71 and are spaced in accordance with the spacing of the key levers. The springs 68 extend downward and rearward from holes 70 to holes 69. With the type bar actions all in normal position, the anchor holes 69 are so arranged that all holes 69 in key levers carrying keys in the same bank are in axial register in a row across the typewriter, but the four rows of holes for the four different banks of key levers 35a, 35b, 35c and 35d are arranged progressively closer to the key lever fulcrum 37 in the just recited order of said banks of key levers, as indicated in Fig. 5.

All four rows of holes 69, in the normal returned condition of the system of type bar actions, are located on a cylindrical locus C5

(Fig. 5) the axis of which is the line on which the row of holes 70 is located. Said rows of holes 69 are equally spaced on said locus in direct proportion to the respective effective lengths of the banks of key levers and are so located on said locus that a straight line can be drawn from the line of the row of holes 70 which will be normal to a chordal line of said locus and will intersect the locus midway between the rows of holes 69 in the first and fourth bank key levers and midway between the rows of holes 69 in the second and third bank key levers.

In the machine shown, the anchor bar 71 extends across the typewriter between the key lever fulcrum bar 38 and the sub-lever fulcrum bar 32 in a rearwardly tilted position affording a compact arrangement of these bars. While the anchor bar 71 may be fixedly supported in various ways, it preferably is supported for slight adjustment of the position of the row of anchor holes 70 in a path at least substantially normal to a chordal line of the locus of the rows of holes 69 intersecting the two outermost rows of holes 69 which path will, of course, be normal to a chordal line of the locus intersecting the two innermost rows of holes 69. For this purpose the rearwardly tilted anchor bar is provided along its lower edge with a forwardly projecting flange 71a the straight front edge of which is rockably seated in a horizontal groove or channel 72 formed in the rear face of the sub-lever fulcrum bar 32. Adjusting and retaining screws 73 pass loosely through holes 74 in bar 71 and are screwed into holes tapped into the fulcrum bar 32 at the rear face of bar 32. By screwing the screws 73 more or less into said holes, the anchor bar may be rockably adjusted. Springs 68 will maintain the anchor bar rocked against the heads of screws 73.

A further feature of the system of type bar actions above described resides in the fact that it affords means for imparting uniform strokes to a straight universal bar for actuating a ribbon vibrator. A straight universal bar 75 depends from, and is fixed on, a rock shaft 76 which is journaled at 77 in side plate 11 and is journaled at 78 in a bracket 79 fixed to side plate 12. A rock arm 80 fixed on said shaft carries a universal bar return stop 81 which normally engages a stop finger 82 on bracket 79. A universal bar return spring 83 is attached to a rock arm 84 fixed on the shaft. The spring normally holds the universal bar rocked into contact with the rounded upper ends 48e of the bellcrank arms 48 with stop 81 engaged with stop finger 82. Rock arm 84 is connected by suitable linkage (shown in part at 85) to a ribbon vibrator (not shown) to actuate the vibrator at the type strokes.

We claim:

1. In a typewriter, a type action comprising a pivoted front strike type bar, an upstanding sub-lever of the third class connected at its upper end to the type bar to swing the bar into printing and rest positions, a sub-lever of the first class forward of the third class sub-lever, a fore and aft extending key lever of the second class carrying its key at its forward end, said sub-levers and key lever having their respective fulcrum axes extending horizontally across the machine in parallelism, a link connecting the third class sub-lever between its ends with one arm of the first class sub-lever to form with said arm a normally extended toggle arranged to fold to exert a continuously accelerating pull on the

third class sub-lever throughout the printing strokes of the type bar, and a link connecting the other arm of the first class sub-lever with the key lever forward of the key lever fulcrum axis to form with said key lever a key-carrying and normally extended toggle arranged to fold to exert both a continuously accelerating pull on said other arm of the first class sub-lever and a continuously increasing resistance to downward rocking of the key lever throughout the printing strokes of the type bar when the key of the key lever is depressed at a constant rate.

2. In a typewriter, a type action comprising a key lever extending forwardly from a transverse horizontal pivot, a first sub-lever having first and second arms extending from a pivot parallel to that of the key lever, a first link connected by transverse horizontal pivots to the key lever and the first arm of said first sub-lever, a second sub-lever extending upward from a pivot between and parallel to those of the key lever and first sub-lever, a second link connected by transverse horizontal pivots to the second arm of the first sub-lever and to the second sub-lever between the ends of the second sub-lever, a front strike type bar pivotally mounted in the typewriter and connected with the upper end of the second sub-lever to be swung through a printing stroke of fixed length by downward rocking of the key lever, and spring means for restoring the aforesaid parts to a normal condition of rest in moving from which, into a condition in which the type bar is in printing position, the first link becomes decreasingly inclined to the key lever and increasingly inclined to the first arm of the first sub-lever while the second link becomes decreasingly inclined to the second arm of the first sub-lever.

3. In a typewriter, a type action comprising a key lever and first and second sub-levers each rockable about a different one of three parallel horizontal fulcrum axes which extend transversely of the typewriter, said first sub-lever having first and second arms and said second sub-lever having a single and upstanding arm, a first link connected by horizontal transverse pivots to the key lever between the key and the fulcrum axis of the key lever and to the first arm of the first sub-lever, a second link connected by horizontal pivots to the second sub-lever between the upper end and the fulcrum axis of that sub-lever and to the second arm of the first sub-lever, and a normally cumbent front strike pivoted type bar having a type carrying arm and a heel portion, a third link having a forward end pivotally connected to the upper end of the second sub-lever and a rear end pivotally connected to the heel portion of the type bar, the pivots of the first link being so arranged that a normal inclination of said link to the key lever decreases and a normal inclination of said link to the first arm of the first sub-lever increases throughout printing strokes of the type bar in response to downward rocking movements of the key lever, and the pivots of the second link being so arranged that a normal inclination of said link to the second arm of the first sub-lever decreases throughout printing strokes of the type bar in response to downward rocking movements of the key lever.

4. A typewriter, as claimed in claim 3, wherein the type bar carries lower and upper case type, and wherein means are provided for bodily case shifting the type bar relatively to said key lever and to the two sub-levers into positions for lower

and upper case typing, in both of which positions the pivotal connection of the third link with the heel portion of the type bar is equidistant from the pivotal connection of said link with the upper end of the second sub-lever.

5. A typewriter having a system of type actions which comprises a system of type keys arrayed across the typewriter in a plurality of fore and aft spaced and horizontal transverse rows, 10 a system of key levers carrying said keys and extending rearward to a common straight and horizontal transverse fulcrum axis, a system of sub-levers fulcrumed at one end of each sub-lever to rock about a common fulcrum axis parallel to that of the key levers, said sub-levers increasing in length from the middle to the sides of the sub-lever system and having their other ends normally arrayed in an arc across the typewriter, 15 a system of pivoted type bars normally arrayed in an arc concentric with that of said other ends of the sub-levers and connected with said ends for movement through like printing strokes to a common printing point, a system of congruent and parallel toggles extending from the sub-levers to a common fulcrum axis parallel to those of the key levers and sub-levers, 20 said toggles having hinge pivots and anchoring pivots to the sub-levers which are equally spaced and respectively normally located on different ones of two cylindrical loci concentric with the toggle fulcrum axis, said anchoring pivots of said toggles being connected to the sub-levers at uniform leverage points, and connections between the respective key levers and toggles for actuating the toggles to the same extent in sub-lever accelerating direction by equal depressions of the respective keys to drive the respective type bars through complete printing strokes.

6. A typewriter having a system of type actions which comprises a system of key levers extending forward from a straight and horizontal transverse fulcrum axis and supporting their keys in fore and aft spaced transverse rows, 25 a system of normally cumbent and forwardly extending type bars pivotally supported in an arcuate array to strike upward and rearward through printing strokes of identical lengths to a common printing point, a system of upstanding sub-levers of the third class extending upward from a common fulcrum axis parallel to that of the key levers with their upper ends connected with the type bars to drive the latter and normally arrayed concentrically with the array of type bars, a system of sub-levers of the 30 first class having a common fulcrum axis also parallel to that of the key levers, a system of links each having a pivotal connection with one arm of a different one of the first class sub-levers and a pivotal connection at a constant leverage point with a different one of the third class sub-levers, the two pivotal connections of all of said links being equally spaced and arranged on different ones of two cylindrical loci which are concentric with the fulcrum axis of the 35 first class sub-levers, and a system of links variably connecting the key levers supporting keys in different rows to the other arms of said first class sub-levers to rock those sub-levers through angles of the same amplitude per unit depth of 40 key depression.

7. A typewriter having a system of front strike type actions comprising a system of key levers extending forward in the typewriter from a straight and horizontal transverse fulcrum axis 45 and presenting fore and aft spaced horizontal

15

rows of keys parallel to said axis, a system of upstanding sub-levers of progressively increasing heights from the middle to the sides of the system and having a horizontal fulcrum axis at their lower ends parallel to and forward of that of the key levers, a system of pivoted front strike type bars connected with the upper ends of the sub-levers to be swung through printing strokes of identical amplitude by forward movements of the upper ends of the sub-levers through arcs of identical chordal amplitude, a system of congruent toggles radiating from a fixedly located fulcrum axis parallel to and forward of those of the key levers and sub-levers to pivotal connections with said sub-levers located at uniform leverage points on the sub-levers and on a cylindrical locus concentric with said fulcrum axis of the toggles, all of said toggles normally being identically and substantially fully straightened, and means connecting the key levers and toggles for folding of the toggles identical extents by identical depression strokes of the keys.

8. A typewriter, as claimed in claim 7, wherein in the means connecting the key levers and toggles includes means for equalizing the initial purchase on the toggles of keys in different key rows.

9. A typewriter, as claimed in claim 8, wherein in the means connecting the key levers and toggles further includes means to progressively decrease the key purchase on the toggles through the depression strokes of the keys.

10. A typewriter having a system of front strike type actions comprising a system of upstanding sub-levers having their upper ends arranged in an arc which curves upwardly from the middle toward the sides of the typewriter and having at their lower ends a common straight and horizontal transverse fulcrum axis, a system of pivoted front strike type bars connected with the upper ends of the sub-levers to be swung through printing strokes of identical amplitude by forward movements of the upper ends of the sub-levers through arcs of identical chordal amplitude, a system of congruent toggles each having first and second members connected by a hinge pivot, the first members of the toggles having a fixedly located common fulcrum axis forward of and parallel to that of the sub-levers and having extensions forward of their fulcrum axis, the second members of the toggles having pivotal connections to the sub-levers at uniform leverage points on the sub-levers which normally are located on a cylindrical locus concentric with the fulcrum axis of the first toggle members, the hinge pivots of the toggles normally being located on a second smaller cylindrical locus concentric with the first mentioned locus, a second system of congruent toggles having pivotal connections at one end to said extensions of the first toggle members of the other system of toggles and extending rearward therefrom to a common fixedly located fulcrum axis parallel to that of said first members of the other system of toggles, and a system of type keys carried each by a different toggle of said second system of toggles for folding the latter toggles as the keys are depressed.

11. A typewriter, as claimed in claim 10, in which the keys are arranged in fore and aft spaced straight and horizontal rows, and wherein in the pivotal connections of the toggles of the second toggle system with said extensions of the first toggle members of the other toggle system are arranged to decrease the normal initial pur-

16

chase of said toggles on said extensions in accordance with the increase of the distance of the key rows from the rear one to the front one of said rows from the fulcrum axis of the toggles of the second system and also to progressively decrease the initial toggle purchase on said extensions throughout depression strokes of the keys.

12. A typewriter having a system of front strike type actions comprising a system of first, second, third and fourth bank key levers of the second class, a system of fore and aft extending sub-levers of the first class, a system of upstanding sub-levers of the third class increasing in height from the middle to the ends of the system, means affording common straight and horizontal transverse fulcrum axes for the three lever systems with the axis for the system of upstanding sub-levers intermediate those for the key levers and the fore and aft extending sub-levers, a first system of links of identical lengths having pivotal connections with the upstanding sub-levers and the rear arms of the fore and aft extending sub-levers, the pivotal connections of said links with the upstanding sub-levers being located at uniform leverage points on said sub-levers and on a cylindrical locus concentric with the axis of the fore and aft extending sub-levers, the pivotal connections of said links with the rear arms of the fore and aft extending sub-levers being located on a smaller and concentric cylindrical locus, a second system of links of identical lengths having normally axially aligned pivotal connections with all of the key levers and having pivotal connections with the forward arms of the fore and aft extending sub-levers which normally are axially aligned for those links connected to any one bank of key levers but which normally are located at distances from the fulcrum axis of the fore and aft extending sub-levers which increase for links connected to each bank of key levers following the first bank, and a system of pivoted front strike type bars connected with the upper ends of the upstanding sub-levers to be swung through printing strokes by depression strokes of the key levers.

13. A typewriter, as claimed in claim 12, wherein in the type bars are connected to the upstanding sub-levers by links of like lengths, and wherein the system of type bars is mounted for ease shifting movements relatively to the three lever systems.

14. A typewriter, as claimed in claim 12, wherein in the two systems of sub-levers and the two systems of links both extend across the typewriter and below the system of type bars, the fulcrum axis of the key levers extends across the typewriter and below the system of type bars, and the keys of the four banks of key levers extend in rows across the typewriter adjacent the system of type bars.

15. A typewriter, as claimed in claim 12, having a system of type action returning springs of like lengths and power anchored at one end to the upstanding sub-levers at uniform leverage points on said sub-levers and normally extending parallel to each other, and also having means stationarily anchoring the other ends of said springs, the anchored ends of the system of springs normally lying in two parallel planes.

16. A typewriter, as claimed in claim 15, having lever adjustable means for shifting the plane of the stationarily anchored ends of the springs toward and from the plane of the other

anchored ends of the springs and in a path normal to the latter plane.

17. A typewriter, as claimed in claim 16, having for the key levers a system of counterbalancing springs of like length and power which are stationarily anchored on a line parallel to the fulcrum axis of the key levers and are anchored to the respective banks of key levers at points on a cylindrical locus concentric with said line, the spring anchor points to the key levers of different banks approaching the key lever axis in order from the first to the fourth bank key levers.

18. In a typewriter, a system of front strike pivoted type bars supported for identical printing strokes from normally cumbent positions in an arcuate array of said bars that rises toward the sides of the machine, a system of type key levers extending rearward from a multiple row keyboard to a straight and horizontal transverse key lever fulcrum axis, a first system of sub-levers upstanding from a fulcrum axis parallel to that of the key levers and having their upper ends arrayed in an arc concentric with that of the type bar array, means connecting the upper ends of said sub-levers with the type bars to swing the type bars through printing strokes and return strokes, a second system of sub-levers having front and rear arms extending from a fulcrum axis forward of and parallel to that of the first system of sub-levers, a system of links having identically spaced horizontal pivotal connections with the upstanding sub-levers and the rear arms of the other sub-levers, said pivotal connections being located on two cylindrical loci which are of different diameters and are concentric with the fulcrum axis of the second system of sub-levers, the pivotal connections with the upstanding sub-levers being located on the locus of greater diameter and at uniform leverage affording points on said upstanding sub-levers, connections between the key levers and the forward arms of the second system of sub-levers for rocking said arms downward by depression strokes of the key levers, the rear arms of the second system of key levers being of identical size and shape and normally being in register across the typewriter, and a straight universal bar extending across said identical sublever arms and supported for actuation by said arms on depression strokes of the key levers.

19. A typewriter having a system of type actions comprising a system of upstanding sub-levers rockable about a common straight horizontal fulcrum axis which extends transversely of the typewriter with the upper ends of the sub-levers normally arrayed in an arc which curves upwardly toward opposite sides of the typewriter, a system of pivoted front strike type bars connected with the upper ends of the sub-levers to

55

60

be swung through printing strokes of identical amplitude by forward movements of the upper ends of said sub-levers through arcs of identical chordal amplitude, a system of congruent parallel toggles extending from a common fixed fulcrum axis which is forward of and parallel to that of the sub-levers to pivotal anchorages which are located at uniform leverage points on the respective sub-levers, said toggles normally being in identically extended conditions in which their hinges are located on one cylindrical locus concentric with the toggle fulcrum axis and their anchorages to the sub-levers are located on a second and concentric cylindrical locus of larger radius, and a system of depressible keys connected with the respective toggles to swing the toggle hinges upwardly and forwardly about the toggle fulcrum axis on the depression strokes of the keys to impart printing strokes to the type bars.

20. A typewriter having a system of type actions comprising a system of upstanding sub-levers rockable about a common straight horizontal fulcrum axis which extends transversely of the typewriter, said sub-levers having their upper ends normally arrayed in an arc which curves upwardly toward opposite sides of the typewriter, a system of pivoted front strike type bars connected with the upper ends of the sub-levers to be swung through printing strokes of identical amplitude by forward movements of the upper ends of said sub-levers through arcs of identical chordal amplitude, a system of congruent and parallel toggles having a common fixed fulcrum axis parallel to the sub-lever axis, said toggles normally being identically and substantially full straightened and having pivotal anchorages to the sub-levers at uniform leverage points on the respective sub-levers which normally lie on a cylindrical locus which is concentric with the fixed fulcrum axis of the toggles, a system of key levers which extend forward from a fixed fulcrum axis parallel to that of the toggles and support a plurality of fore and aft spaced rows of keys at the front of the typewriter, and a system of individual connections between the key levers and toggles for folding the toggles identical extents at identical accelerating speed rates by depression strokes of the keys of identical extents and identical constant speed rates.
